UNITED STATES PATENT OFFICE.

JAMES B. STRONG, OF HILLBURN, NEW YORK.

CROSSOVER.

1,382,869.

Specification of Letters Patent. Patented June 28, 1921.

Application filed August 28, 1920. Serial No. 406,606.

To all whom it may concern:

Be it known that I, JAMES B. STRONG, a citizen of the United States, and resident of Hillburn, in the county of Rockland and 5 State of New York, have invented certain new and useful Improvements in Crossovers, of which the following is a specification.

The invention relates to a railroad crossover of the built-up type which is provided 10 on opposite sides with wheel tread engaging members for assisting the flanged wheels of the railroad vehicle past the cross-over and which due to their function of protecting the flanges of the wheels, will be referred to 15 hereinafter by their commercial name of flange guards and easer joints. The present application constitutes a companion case with a similar application filed under even date and having Serial No. 406,605.

20 In the companion application there was featured a solid frog construction in which a combined flange guard and easer joint were formed in one piece and demountably secured on opposite sides of the main part of 25 the solid frog structure and in which the solid frog construction also formed a base support for the combined flange guard and easer joint.

The present disclosure constitutes, in effect, a modification of the showing in the 30 above identified application in that the demountable flange guard featured in the prior application is assembled with a built-up frog of some conventional form to provide 35 a simple and readily formed type of flange guarded cross-over which will permit the ready replacement of worn parts without the necessity of scrapping either the entire frog or any unworn parts thereof.

40 Another object of the invention is to provide a frog construction of the type outlined, the parts of which can be made up from standard parts and slightly modified *in situ*, if necessary, to form any particular character or size of frog desired in any particular 45 location.

Still another object of the invention is to provide a simplified tying means for securing the assembled parts of the frog construction in fixed position relative to each other 50 and at the same time to secure the flange guards in set position and yet in position so that they may be readily replaced.

Various other objects and advantages of 55 the invention will be in part obvious from an inspection of the accompanying drawings

and in part will be more fully set forth in the following particular description of one form of mechanism embodying my invention, and the invention also consists in certain new and novel features of construction and combination of parts hereinafter set forth and claimed.

In the accompanying drawings:

Figure 1 is a plan view of a frog construction illustrating a preferred embodiment of the invention and

Figs. 2 and 3 are each transverse sectional views taken respectively on the lines 2—2 and 3—3 of Fig. 1 looking in the direction indicated by the arrows.

In the following description and in the claims, parts will be identified by specific names for convenience of expression but they are intended to be as generic in their 75 application to similar parts as the art will permit.

In the drawings, there are shown the usual supporting ties at the cross-over positioned on which is a built-up frog construction which is of more or less conventional form and which has been selected to show the application of the replaceable guards to a conventional structure. In Fig. 1 there is shown a pair of service rails 10 and 11 disposed at an angle to each other and with their adjacent ends cut to a bevel and connected to form the frog point 12. Another pair of rails 13 and 14 are disposed for their main length at an angle to each other and 80 designed to form continuations respectively of the rails 11 and 10 across the joint. The service rails 13 and 14 are extended past the point 12 on opposite sides thereof and have their end portions bent outwardly to form 85 flared ends and are spaced apart by filler blocks 20. The point 12 is held in position midway between the portions of the rails 13 and 14 within the outlines of the frog and identified hereinafter as wing rails, by 90 wedge filler blocks 21 and 22 disposed on opposite sides of the point. Certain of the parts are held together by through bolts 23 and it is to be understood in general that the 95 construction as thus far described is of conventional form.

The organization of parts so far recited to form the frog is mounted upon one or more base plates 24, which in Fig. 1 are shown to be three in number, and positioned on adjacent ties. The base plates are of wide, practically flat steel plates, are of similar form

and extend transversely of the length of the frog. The base plates are provided at opposite ends with upstanding shoulders 25 constituting projections preferably formed integral with the plates, disposed in spaced relation to the wing rails, and positioned on opposite sides thereof as shown in Fig. 2. A pair of preformed castings 26 each constituting a combined flange guard and easer 10 joint are positioned on opposite sides of the frog construction and lap the point 12 as shown more particularly in Fig. 1. The wheel rim engaging portion 27 of the member 26 is widened toward the heel end of 15 the same to provide a broad surface 27' which overlaps the rail at this point and constitutes a tread guard.

The flange guard 26 is provided on its inner side with an upstanding member 29 20 shaped to fit snugly against the adjacent face of the wing rail and rests at its lower end upon the upper face of the lower outer flange 30 of the engaged wing rail. The guard also includes an outwardly extending 25 bottom flange 31 with the lower face 32 designed to be disposed in the common plane which contains the lower faces of the several surface rails so as to provide a broad bearing surface for engaging the base plate 24 30 or other support for the construction. Long through bolts 33 are passed through the service rails, through the interspacing filler blocks and through one or both of the flange guards so as to securely fasten the several 35 parts rigidly in position and yet to fasten the parts so that they may be readily demounted for replacement or repair.

Supplementing this means for connecting the parts together additional means are 40 illustrated for locking the combined frog construction with its guard rails to the base plate 32. For this purpose wedges 34 are driven between the projecting shoulder 25 on one side and the adjacent flange 31 which 45 wedges are locked to the base plate by bolt and slot connections 35 provided with lock nuts 36. It is obviously within the scope of the invention to duplicate the wedge on opposite sides of the construction.

50 In order to more effectively lock the parts in position in the situation where at least two base plates are used the construction of the lower flange of the guards illustrated in Fig. 1 is suggested. In this showing the 55 outer edge 41 of one of the flanges 31 is inclined inwardly to form converging sides 37 and the flange engaging edges 38 of the wedges are cut at an angle to the length of the slot in the slotted construction 35 to 60 engage the inwardly and centrally directed edge 37 in such a manner that moving the wedges away from each other and longitudinally of the length of the construction on each side will tend in their effort to move 65 the guard in opposite directions to press the

same inwardly. This wedge construction acting in this manner on opposite sides of the frog will form a rigid, solid construction free of any looseness of parts and capable of withstanding strains to which such 70 devices are subjected in a manner which has proven entirely satisfactory in practical operation.

It is usually true that due to the fact that traffic is heavier in one direction than the 75 other over any particular joint, one of the guard rails will wear away more rapidly than the other. In order to replace any such worn rail in the device disclosed it is simply necessary to remove the holding bolts, loosen 80 the wedges, remove the worn rail and replace the same with a new guard and this replacement can be effected practically without changing any of the parts of the built-up frog construction and even without removing the through bolts from their position. It is possible with the construction disclosed to make changes in the relative arrangement of the service rails, simply by shifting the wedging filler blocks or replacing 85 the same with other filler blocks of a different size and this can be effected while using a standard form of combined flange guard and easer joint. Not only can the flange guard be replaced when worn without 90 affecting the present position of the frog but the service rails may likewise be replaced simply by loosening the wedges and withdrawing the through bolts, inserting the new rail in position and tightening up the 95 wedges and bolt carrying means. As this substitution of parts can be effected quickly no material interruption is necessary to the 100 service across the frog.

In those situations where the wedge plates 105 are confined to one side of the structure as shown in Fig. 1, the flange 31 is provided with extensions 39 which engage against the adjacent shoulders 25 and are secured to the base plate by bolts 40.

While I have shown and described, and have pointed out in the annexed claims, certain novel features of my invention, it will be understood that various omissions, substitutions and changes in the form and details of the device illustrated and in its operation may be made by those skilled in the art without departing from the spirit of the invention.

Having thus described my invention, I 120 claim:

1. In a built-up railroad frog construction, the combination of a pair of service rails extending at an angle to each other, engaging at one end and fashioned to form the point of the frog, a second pair of transversely spaced apart service rails extending at an angle to each other, designed to form continuations of the first named pair across the frog and constituting wing rails extending on op- 125 130

posite sides of and continuous beyond the point, wedging filler blocks disposed between the service rails and between the point and the outside wing rails to hold the point in fixed position relative to the wing rails, a pair of combined flange guards and easer joints, each including an upstanding inner part resting on the lower flange of one of the wing rails, and having a configuration to fit the outer face of said wing rail opposite the point and also including a downwardly and outwardly inclined extension in spaced relation to the inner part and having an outwardly extending supporting flange and through bolts passing through the service rails, through the filler blocks and through the combined flange guards and easer joints to tie the built-up construction together.

2. In a built-up railway frog construction, the combination of a base plate extending laterally of the length of the construction, a pair of service rails fashioned to form the point of the frog disposed on said base plate, a pair of transversely spaced apart service rails disposed on said base plate disposed to the outside of and spaced from the point, wedge filler blocks disposed between the point and the outside rails to hold the same in fixed relative position, flange guards fitted to the outer sides of the outside rails and disposed on said base plate, and wedging means between the base plate and the flange guards for securing the parts of the construction rigidly in position.

3. In a built-up frog construction, the combination with a base plate, two pairs of service rails resting on said base plate, and spacing filler blocks disposed between the service rails and coacting therewith to form a built-up frog construction, with certain of the service rails provided on their outer sides with guard receiving faces, of flange guards engaging said faces resting on said base plate and wedging means disposed between the base plate and guards for securing the guards in engagement with the frog construction.

4. In a rail frog construction the combination of a base plate having an upwardly extending projection adjacent one end, a frog construction resting on said plate in spaced relation to the projection and having a guard receiving surface facing the projection, a flange guard on said plate engaging said surface and a wedge driven between the projection and flange guard to secure the same in place relative to the frog construction.

5. In a rail frog construction, the combination of a base plate provided with wedge engaged extensions at opposite ends, a frog construction extending across the plate, disposed between the extensions and in spaced relations thereto, a pair of flange guards demountably positioned on opposite sides of the frog construction and engaging the same and a wedge disposed between each extension

from the plate and the adjacent flange guard, said wedges coacting to secure the flange guards and frog construction in fixed position relative to each other and to the base plate.

6. In a rail frog construction, the combination of a base plate having an upwardly extending projection adjacent one end, a frog construction resting on said plate in spaced relation to the projection and having a guard receiving surface facing the projection, a flange guard engaging said surface and a wedge driven between the projection and flange guard to secure the same in place relative to the frog construction, a frog-construction-securing-bolt horizontally disposed and spaced from the base plate for securing the flange guard to the frog construction independently of, and supplementing, the securing effect of said wedge.

7. In a built-up frog construction, the combination with an organization including four transversely disposed rails with the two inner rails coacting to form the frog point and said rails having bottom flanges with their bottom faces disposed in a common horizontal plane, and filler blocks disposed between the rails, of a flange guard having a wide spreading base including an upstanding member engaging the outer face of one of the outer rails and resting on the top side of the lower flange of said engaged outer rail, said flange guard also having an outer, inclined member provided with an outwardly extending bottom flange with its bottom face disposed in the plane of the bottom face of the rails and means for securing the flange guard to said organization of rails and interposed filler blocks.

8. In a built-up frog construction the combination with an organization including four transversely disposed rails with the two inner rails coacting to form the frog point and said rails having bottom flanges with their bottom faces disposed in a common horizontal plane, of a flange guard including an inner part engaging the outer face of one of the outer rails with the lower portion thereof engaging the top side of the lower flange of said engaged outer rail, said flange guard also including an outer part spaced from the inner part and provided with an outwardly extending bottom flange with its bottom face disposed in the plane of the bottom face of the rails, and means to secure the same in set position.

9. In a railway frog construction, the combination of an organization of parts forming a frog, a flange guard engaging the frog along one side thereof, said guard provided with an outwardly extending bottom flange, the outer edge of said flange converging inwardly toward the central portion of the flange, and wedges acting in opposite directions longitudinally of the

frog and engaging said inclined edges in opposite directions.

10. In a railway frog construction, the combination of an organization of parts forming a frog, a flange guard engaging the frog along one side thereof, said guard provided with an outwardly extending bottom flange, the outer edge of said flange converging inwardly toward the central portion of the flange, wedges acting in opposite directions longitudinally of the frog, engaging said inclined edges in opposite directions, and means for locking the wedges in position.
15. 11. In a railway frog construction, the combination with a base plate having an upwardly extending projection at opposite

ends, an organization of parts forming a frog disposed on the plate between the projections, a flange guard disposed between 20 each projection and the adjacent side of the frog construction, each guard provided with a bottom flange resting on the base plate, the outer edge of each of said bottom flanges converging inwardly toward the mid-length 25 of the flange, and wedges disposed between each projection and the adjacent inwardly inclined edge of the contiguous bottom flange.

Signed at New York in the county of 30 New York and State of New York this 23rd day of August.

JAMES B. STRONG.
